US00D557588S

(12) **United States Design Patent** (10) **Patent No.:** **US D557,588 S**
Stifle et al. (45) **Date of Patent:** **** Dec. 18, 2007**

(54) **ELECTRONIC KEY**

(75) Inventors: **William Stifle**, Rogers, MN (US); **Dean Daniels**, Rosemount, MN (US)

(73) Assignee: **Datakey Electronics, Inc.**, Savage, MN (US)

(**) Term: **14 Years**

(21) Appl. No.: **29/265,029**

(22) Filed: **Aug. 23, 2006**

(51) LOC (8) Cl. **08-07**

(52) U.S. Cl. **D8/347**

(58) Field of Classification Search D8/330-348; 70/353, 402, 405, 413, 272, 336, 344, 277, 70/252; 235/382; D20/22

(57) **CLAIM**

We claim the ornamental design for an electronic key, as shown and described.

DESCRIPTION

FIG. 1 is a top, front, and right side perspective view of an electronic key.

FIG. 2 is a front elevational view of the electronic key of FIG. 1.

FIG. 3 is a rear elevational view of the electronic key of FIG. 1.

FIG. 4 is a left side view of the electronic key of FIG. 1.

FIG. 5 is a right side view of the electronic key of FIG. 1.

FIG. 6 is a top plan view of the electronic key of FIG. 1; and, FIG. 7 is a bottom plan view of the electronic key of FIG. 1.
